UNITED STATES PATENT OFFICE.

JACOB JACOBY, OF NEW YORK, N. Y.

NURSING-WAIST.

1,013,778.

Specification of Letters Patent.

Patented Jan. 2, 1912.

Application filed April 18, 1911. Serial No. 621,742.

To all whom it may concern:

Be it known that I, JACOB JACOBY, a citizen of the United States, and a resident of the city of New York, borough of Manhattan, in the county and State of New York, have invented a new and Improved Nursing-Waist, of which the following is a full, clear, and exact description.

The invention relates to wearing apparel, and its object is to provide a new and improved nursing-waist arranged to permit the use of an embroidered or open mesh front, to allow convenient opening at either side of the front for nursing purposes, and to thoroughly protect the body of the wearer and avoid undue exposure while nursing. In order to accomplish the desired result, use is made of bust openings or plackets at the sides of the front, and inside flaps are attached at their outer edges to the body of the waist at the inside thereof, the inside flaps extending toward each other and having their free edges overlapping at the middle and in the rear of the front, and having means for fastening the free edges of the inside flaps together.

A practical embodiment of the invention is represented in the accompanying drawings forming a part of this specification, in which similar characters of reference indicate corresponding parts in all the views.

Figure 1 is a perspective view of the nursing waist, as applied, and showing one of the bust openings or plackets open; Fig. 2 is an enlarged rear elevation of the nursing waist showing the back opened up; and Fig. 3 is a sectional plan view of the nursing waist, showing the several parts in closed position.

The body A of the waist is provided with a suitable neck band B and arms C, and the back D of the body is opened along the middle and the overlapping edges D' of the back are adapted to be fastened together by buttons and button-holes, or other fastening devices, E, as plainly indicated in Figs. 2 and 3. The front F of the body A is provided at the sides with bust openings or plackets G extending from near the shoulders to within a distance above the waist line, as plainly indicated in Fig. 1,

and the said bust openings G are adapted to be closed by buttons and button-holes or other fastening devices H when not in use.

To the inside of the body A at the front thereof are secured the outer edges of inside flaps I, I', having their free ends I², I³ overlapping at the middle and in the rear of the front, and the said overlapping edges I² and I³ are adapted to be fastened together by buttons and button-holes or other fastening devices J. The outer edges of the inside flaps I and I' are secured to the body A a distance rearward from the placket openings G, and the said flaps I and I' are secured at their upper ends to the neck band B and the shoulder portions of the body, a portion of the side edges overlying the front portion of the armhole to extend from the bottom of the armhole down to the lower end of the front of the body. It is understood that normally the inside flaps I and I' as well as the plackets G are closed, and for nursing purposes it is necessary to open the first opening G as well as the overlapping edges I², I³ at the inside flaps I and I'.

By having the inside flaps I and I' extending across the front F of the body A and in the rear of the said front, it is evident that the latter may be of an open mesh or embroidered fabric, thus enhancing the appearance of the nursing waist without exposing the body of the wearer, as the latter is covered and thoroughly protected by the inside flaps I and I'. It will also be noticed that the inside flaps I and I' practically form a corset cover.

Having thus described my invention, I claim as new and desire to secure by Letters Patent:

A combination nursing waist and corset cover, comprising a waist body open at the back and having an integral front, the side edges of which form with the said body bust openings, the sides of the front and the said body having overlapping members at the bust openings, fastening devices for fastening the said members together, and a corset cover in the rear of the said front and formed of flaps secured at their outer edges to the said waist body at a point to

the rear of the said bust openings, the upper edges of the said flaps being secured to the neck of the waist body, the said flaps overlying the said bust openings and having their inner edges overlapping, and fastening means for fastening the said overlapping inner edges of the flaps together.

In testimony whereof I have signed my name to this specification in the presence of two subscribing witnesses.

JACOB JACOBY.
